ELECTRON TUBE

Gunther Jobst and Horst Rothe, Berlin, Germany, assignors to Telefunken Gesellschaft für Drahtlose Telegraphie m. b. H., Berlin, Germany, a corporation of Germany

Application October 28, 1933, Serial No. 695,568
In Germany October 31, 1932

9 Claims. (Cl. 250—27.5)

Various constructions of multi-tubes are already known with which it is aimed on the one hand at saving space in the receiver and on the other hand at decreasing the cost of the set of tubes required for the receiver. In general such multi-tubes are so constructed that individual or separate electrode systems are arranged side by side within the glass bulb. Often a common cathode is used for all the systems, and since the 5 various electrode systems are arranged alongside the cathode, the latter has a correspondingly great length. Such tube is shown schematically in Figure 1 wherein the left half is a screen grid tube serving for high-frequency amplification, while the part at the right side operates as a space charge grid tube employing a regenerative or feed-back coupling circuit for reducing damping. While the support of through electrodes of a concentrically constructed system 10 can easily be accomplished by supporting the one end and by spacing the other end, the mounting of such multi-systems in a press involves considerable difficulties in point of construction and mechanical consideration, since the through 15 electrodes require a greater number of supporting points.

According to the present invention individual or separate electrode systems are not placed adjacent to each other along the cathode, but instead the electrodes, preferably of about the 20 length of the entire system, are arranged behind each other and certain parts of said electrodes are constructed differently in the direction of the cathode in regard to spacial dimensioning, 25 shaping, and permeability to current. The grid electrodes are of particular concern in this respect, the diameter of which and the spacing of its turns being capable of variations within wide limits. Also the provision of inactive places in 30 the electrode surfaces and the covering of only a portion of the cathode length by some electrodes are to be considered modifications in the shape of the electrode systems in the direction of the cathode. In this manner it is possible to 35 arrange different electrode combinations opposite various parts of the cathode so that the electron current leaving the cathode will be divided into separate current paths, controlled in various manner. In accordance as to whether a 40 possibly independent control, or a certain relation on which these paths depend, is intended, the variation in the shaping of the electrodes can be made within sudden steps and within extreme 45 differences or a gradual zone can be provided 50 therebetween. Further possible embodiments 55

reside in the fact whether or not for different electrodes the variation of the form of places above each other is carried out in the same plane through the cross-section. As will be more specifically explained with reference to further 5 embodiments, the variation of the form of different electrodes may also be carried out in an opposite sense, for instance by a decrease in the diameter of one electrode from left to right while for another electrode this takes place in 10 the opposite direction. It is further conceivable that the conditions in the "through grip" within the sections of the electrode system continuously varies, which sections result from the various 15 shaping of single electrodes and that such condition may serve to cause the characteristic of the respective current path to take a course different from that obtained in accordance with the E_{st} 3/2-law (E_{st} =control voltage).

In the type of tubes hitherto known in which 20 in the direction of the cathode a different shaping of electrodes was provided, such measure was resorted to in a different manner as well as for other purposes, for instance in order to obtain a logarithmic course of the characteristic, or to 25 compensate the voltage drop along the filament of directly heated incandescent cathodes and to produce a homogeneous field distribution. In the present case however, on the contrary, it is aimed at a non-homogeneous control action 30 and at the formation of adjacent electron current paths independently influenced to different extents by the individual electrodes.

Figure 2 shows an embodiment, by way of example, of such a tube having the same properties 35 as the double tube shown in Figure 1. Particular emphasis is laid on the extreme differences in the pitch of the grid turns. In the left half the grid G_1 surrounding the cathode C is closely wound whereas at the right the turns are very 40 far apart, denoting in the extreme case that the grid bars are without turns, so that on this side the flow of the electron current is not or only to a small extent influenced by the electrode. The succeeding grid G_2 is common to both halves 45 although acting on the left side as screen grid and on the right side as space charge grid, and it is uniformly constructed over the entire length of the system. In the left half the electrode G_3 in front of the plate P has a very large grid winding pitch whereas in the right half the pitch 50 is small. In this case the left part of the electrode has no notable controlling action. As regards electrical effects the tubes according to 55 Figures 1 and 2 are not distinct from each other 55

yet it will be noted from Figure 2 that the electrode system in this figure can be mounted in the same simple manner as that of any single tube.

5 Figure 3 is intended to elucidate the practical mounting showing the one side support of the electrodes, which are denoted by the same reference characters employed in Figure 2.

Figure 4 presents a further example of the use of a multi-tube operated in accordance with the features of the present invention. In this case also two current paths are controlled but in an entirely different manner from Fig. 2. The left half of the tube operates as high-frequency amplifier; the first grid G_{c1} is the control electrode; the second grid G_{c2} on this side remains ineffective due to the grid bars being without windings, and the third grid G_p serving as anode for this circuit is so closely wound that the electrode disposed in back thereof has no appreciable through grip. The right half of the tube represents a back coupled audion, the first and third grids G_{c1} and G_p being inactive while the second grid G_{c2} serves as the control grid. In operation the circuit functions in the following manner: The tunable grid circuit A_a , connected between cathode C and grid G_{c1} through the biasing battery B , is tuned to the frequency of the signal to be received. The amplified signal oscillations appear in the output circuit C, S, T_1, G_p, C . The tunable grid circuit A_d , connected between the cathode C and the grid G_{c2} through the grid leak-condenser combination K , is also tuned to the signal frequency and is coupled to the amplifier output circuit through transformer T_1-T_2 . The detector output circuit C, S, T, T_3, P, C is regeneratively coupled to the tuned grid circuit A_d by means of the windings T_3, T_2 , the detected signal being indicated in the telephone T .

40 A further example of a circuit is shown in Figure 5 explaining the use of twin-tubes in a sound transmitter for two frequencies ω_1 and ω_2 . In the left half of the tube the first grid G_1 serves for exciting the frequency ω_2 , while in the right half the other frequency ω_1 is back coupled to the third grid G_3 ; the second grid G_2 is common to both halves and acts as a screen grid and a space-charge grid, respectively. It will be readily seen that such a tube can be employed with particular advantage as a mixer tube in intermediate frequency receivers.

What we claim is:—

1. A multi-function electron discharge tube comprising a cathode, an anode and a plurality of grid electrodes interposed between cathode and anode, the grid electrode nearest the anode being divided along the length of the cathode into distinct portions, each of uniform grid openings, but the grid openings of the various portions being different, said grid portions and corresponding portions of the other grid electrodes cooperating with the cathode and anode to perform different functions.

2. A multi-function electron discharge tube comprising a cathode, an anode and a plurality of helically wound grid electrodes interposed between cathode and anode, the grid electrode nearest the anode being divided along the length of the cathode into distinct portions, each of uniform pitch, but the pitches of the various portions being different, said grid portions and corresponding portions of the other grid electrodes cooperating with the cathode and anode to perform different functions.

3. A multi-function electron discharge tube

comprising a cathode, an anode and a plurality of helically wound grid electrodes interposed between and coextensive with said cathode and anode and surrounding the cathode, the grid electrode nearest the anode being provided with 5 widely spaced but uniform turns for substantially one-half of its length and with closely spaced but uniform turns for substantially the other half of its length, said half-length grid sections and corresponding sections of the other grid electrodes cooperating with the cathode and anode to perform different functions.

4. A multi-function electron discharge tube comprising a cathode, an anode and a plurality of helically wound grid electrodes interposed between and coextensive with said cathode and anode and surrounding the cathode, the grid electrode nearest the anode being provided with 15 widely spaced but uniform turns for substantially one-half of its length and with closely spaced but uniform turns for substantially the other half of its length, the next adjacent grid electrode being provided with uniformly spaced turns throughout its length, said half-length grid sections and corresponding sections of the other 20 grid electrodes cooperating with the cathode and anode to perform different functions.

5. A multi-function electron discharge tube comprising a cathode, an anode and a plurality of helically wound grid electrodes interposed between and coextensive with said cathode and anode and surrounding the cathode, one of said 30 grid electrodes being provided with widely spaced but uniform turns for substantially one-half of its length and with closely spaced but uniform turns for substantially the other half of its length, and a second grid electrode being provided opposite the widely spaced turns of the first mentioned grid electrode with closely spaced but uniform turns and being provided for substantially the other half of its length with widely spaced but uniform turns.

6. A multi-function electron discharge tube comprising a cathode, an anode and a plurality of helically wound grid electrodes interposed between and coextensive with said cathode and anode and surrounding the cathode, the grid electrode nearest the cathode being provided with 45 widely spaced but uniform turns for substantially one-half of its length and with closely spaced but uniform turns for substantially the other half of its length, the next adjacent grid electrode being provided opposite the widely spaced turns of the grid electrode nearest the cathode with closely spaced but uniform turns and being provided for substantially the other half of its length with widely spaced but uniform turns.

7. A multi-function electron discharge tube comprising a cathode, an anode and a plurality of helically wound grid electrodes interposed between and coextensive with said cathode and anode and surrounding the cathode, the grid electrode nearest the cathode being provided with widely spaced but uniform turns for substantially one-half of its length and with closely spaced but uniform turns for substantially the other half of its length, the next adjacent grid electrode being provided with uniformly spaced turns throughout its length and the third grid electrode being provided opposite the widely spaced 60 turns of the grid electrode nearest the cathode with closely spaced but uniform turns and being provided for substantially the other half of its length with widely spaced but uniform turns.

8. A multi-function electron discharge tube 75

comprising a cathode and an anode, a plurality of grid electrodes interposed in the space between said cathode and anode, independent support rods for each of said grid electrodes, and
5 the grid electrode nearest the anode and that adjacent the cathode, each being provided with widely spaced but uniform turns for substantially one half of its length and with closely spaced but uniform turns for substantially the other
10 half of its length, the grid turns of each electrode being mounted on a common support rod for electrical connection to the same potential source.

9. A multi-function electron discharge tube
15 comprising a cathode and an anode, first, sec-

ond and third grids interposed in the space between said cathode and anode, the first grid electrode being provided with widely spaced but uniform turns for substantially one half of its length and with closely spaced but uniform turns for substantially the other half of its length, the second grid being provided with uniformly spaced turns, the third grid being provided opposite the widely spaced turns of the first grid with closely spaced but uniform turns and provided opposite the closely spaced turns of the first grid with widely spaced turns, and independent support rods for each of said grids. 5
